UNITED STATES PATENT OFFICE.

LEWIS MORGAN, OF MANCHESTER, OKLAHOMA, ASSIGNOR OF ONE-HALF TO JAMES JAY WARNOCK, OF MANCHESTER, OKLAHOMA.

WHIFFLETREE-HOOK.

No. 890,082.

Specification of Letters Patent.

Patented June 9, 1908.

Application filed April 23, 1907. Serial No. 369,864.

To all whom it may concern:

Be it known that I, LEWIS MORGAN, a citizen of the United States, residing at Manchester, in the county of Grant, Oklahoma, have invented a new and useful Whiffletree-Hook, of which the following is a specification.

This invention relates to a whiffletree hook provided with means for preventing the trace strap from becoming disengaged. 10 The object of the invention resides in a spring plate of novel form and construction, pivoted near the end of a whiffletree and extending through an opening in a T headed shank, to which the trace is fastened, the 15 spring plate engaging the under side of said shank by means of an offset on said plate.

In the accompanying drawing: Figure 1 is a perspective view of the invention, and Fig. 2 is a longitudinal vertical sectional view of 20 the same.

Similar numerals of reference indicate the same parts in all the figures.

A whiffletree 1 of usual construction is socketed in a tubular end cap 2 from the end of 25 which on its under side projects a flat shank 3 having a neck 4 and a head 5 enlarged in a fore and aft direction as shown. Through the head 5 is a vertical slot 6, the outer wall 7 of which is inclined from above down- 30 wardly and inwardly to form a lip or keeper 8 at the bottom. On the upper side of the cap, and back from its end a suitable distance are two upstanding lugs 9, between which and the end of the cap is a groove 2^a 35 forming a seat for a spring plate 10 pivoted on a pin 11 passing through an eye 12 on said spring plate, and the lugs as shown.

The spring plate 10 is approximately in the form of a right angle having its longer arm 40 10^a slightly curved inwardly, as shown and its shorter arm 10^b provided on its outer side with a projecting lug or head 13, beveled on its under side, to engage below the lip or keeper 8, and two shoulders 14, one on each 45 edge, to rest on the top of the shank 3 and limit the downward movement of the spring plate 10.

The trace strap 15 is attached by its elongated opening 16 to the neck of the shank 3 50 as usual after the spring plate has been disengaged and thrown back, as represented by

dotted lines in Fig. 2. Having placed the trace in position, the spring plate is turned on its pivot until the beveled face of the lug 13 rests on the inclined side 7 of the slot 6. 55 Then, by pressing on the spring plate, the lug slips over the inclined wall 7 and under the lip 8 and locks the plate in position. Where the spring plate passes over the trace, it is curved to give plenty of room for the 60 trace to work without striking the plate. The longer arm of the spring plate is thinner than the shorter arm as it is the former arm which yields when the lug is pressed back to engage and disengage the lip. The longer 65 arm 10^a of the plate spring rests in the groove 2^a when in locked position and guards against lateral movement of said spring.

It will be seen that the spring 10 serves to force the head or lug 13 into engagement 70 with keeper 8 and as a result said spring becomes positively locked in engagement with the keeper and can not be moved out of the opening 6 to release the trace unless the head 13 is first moved against the stress of the 75 spring and away from the keeper, this movement being in the direction of the length of the slot 6.

Having thus described the invention what is claimed is:—

A whiffletree hook comprising a cap, a longitudinally slotted shank extending therebeyond, a spring strip pivotally mounted upon said cap and having a beveled head insertible through the slot, said strip being 85 shaped to spring the head automatically into engagement with one wall of the slot to lock it against withdrawal therefrom, and stop shoulders extending laterally from the spring strip and perpendicularly to the path of 90 movement of the head, said shoulders being designed to loosely rest upon the shank and to slide thereon during the movement of the head into or out of engagement with the wall of the slot.

In testimony that I claim the foregoing as my own, I have hereto affixed my signature in the presence of two witnesses.

LEWIS MORGAN.
